(57) **CLAIM**

I claim the ornamental design for a bottle, as shown and described.

DESCRIPTION

FIG. 1 is a front elevational view of a bottle showing the new design;

FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a perspective view of the top, front, and right sides thereof;

FIG. 8 is a cross-sectional view of the bottle taken along section line 8-8 of FIG. 1;

FIG. 9 is a cross-sectional view of the bottle taken along section line 9-9 of FIG. 1; and,

FIG. 10 is an enlarged cross-sectional view of a portion of the bottle taken along section line 10-10 of FIG. 8.

The article of this design is entirely transparent, and the light, parallel lines shown in each of the figures indicate the transparency of this design.

As shown in the cross-sectional views of FIGS. 8 and 9, and the enlarged cross-sectional view of FIG. 10, patterns and characters (Japanese kanji characters) on the surface of the body portion of the bottle of this design are formed in convex shapes.

The dash-dot broken line in FIG. 10 depicts a symbolic break. The break line and what is shown beyond the break line form no part of the claimed design.

1 Claim, 5 Drawing Sheets
